UNITED STATES PATENT OFFICE.

WALTER P. GRATH, OF ST. LOUIS, MISSOURI.

BRICK-KILN.

1,034,105.

Specification of Letters Patent. Patented July 30, 1912.

Application filed February 11, 1911. Serial No. 608,000.

To all whom it may concern:

Be it known that I, WALTER P. GRATH, a citizen of the United States, and a resident of the city of St. Louis and State of Missouri, have invented a new and useful Improvement in Brick-Kilns, of which the following is a specification.

This invention relates to kilns and more particularly to continuous kilns for burning bricks, tiles, and the like.

It has for its principal objects to secure a simple and inexpensive structure, to save fuel, to secure a uniform burning of the ware, and to attain certain advantages which will hereinafter more fully appear.

The invention consists in the parts and in the arrangements and combinations of parts hereinafter described and claimed.

In the accompanying drawing which forms part of this specification and wherein like symbols refer to like parts wherever they occur,—Figure 1 is a vertical section taken on or about the line $y-y$ of Fig. 2; and Fig. 2 is a horizontal section, the upper half of the figure being taken on or about the line $x-x$, and the lower half of the figure being taken on or about the line $z-z$ of Fig. 1.

The kiln is arranged as a connected series of burning chambers, preferably in a straight row or rows. As shown in the drawing, the respective burning chambers 1 are arched transversely of the row, and each chamber is provided at its opposite ends with doorways 2 through which the bricks, tiles, or other ware are placed into and removed from the kiln. In each end wall of the kiln, on opposite sides of the doorway, are furnaces 3, the same being arranged either for coal, oil, gas, or other suitable fuel. The respective furnaces 3 open into bags 4 through which the products of combustion enter the chamber 1 above the bag walls 5. At each side of the burning chambers are bags 6 whose walls 7 extend to approximately the same plane with the upper edge of the bag walls 5. The lower portions of the bags 6 constitute fuel chambers which are open at their opposite ends as at 8.

The bottoms or floors of the kiln cham-

bers 1 are formed hollow. That is, the floors are provided with alternately disposed perforated and imperforate or radiating flues 9 and 10, respectively. These flues extend transversely of the arched burning chambers, but lengthwise of the row of chambers, and the perforated flue of one chamber is in line and in direct communication with the radiating flue of the adjacent burning chamber on one side. That is, in a row of burning chambers, the communication between a perforated flue of one chamber and the radiating flue of an adjoining chamber is established in one direction only throughout the entire row. In other words, provision is made for conducting the products of combustion or waste gases and heat from the chambers successively to the adjoining chamber in one direction from one end of the row of chambers to the other; and when the chambers are arranged in two parallel rows, communication is established between the perforated and radiating flues of the adjacent endmost chambers by cross flues 11 connected to exit flues 14.

The division walls between the respective burning chambers and also the walls at the ends of the row are provided with vertical flues 12 which communicate with the radiating flues 10 of the respective burning chambers and open into the bags 6 of said chambers above the fuel in said bags, as at 13. Each of the burning chambers is provided with an exit flue 14 beneath the floor and communicating with the respective perforated flues 9, as at 15; while the cross connecting flues 11 connect with the radiating flues 10 of one of the adjacent end chambers as at 16. The exit flues 14 and cross connecting flues 11 are, each and all, adapted to communicate with a single stack or exhaust fan or other draft creating device 17; and suitable dampers 18 are provided so that the respective flues 14 and 11 may be opened and closed as desirable or necessary in operating the kiln.

In the operation of the kiln, when one of the chambers is being fired, the damper 18 in its exit flue 14 may be closed, and the damper in the exit flue of the chamber to the right or on that side of the chamber

which is being fired whose radiating flues 10 communicate with the perforated flues 9 of said chamber being fired is opened. The products of combustion from the furnaces 3 and bags 6 are drawn through the perforations into the respective perforated flues, thence through the imperforate radiating flues, thence up through the openings 12 and 13 and over the bag walls 7 at opposite sides 10 of the adjacent chamber 1, and thence down through the perforated flues of said adjacent chamber and out through its exit flue 14 to the exhaust fan or stack 17. Hence, the products of combustion or waste heat 15 from the fired chamber is utilized in the preliminary heating of an adjoining chamber on one side; while the waste heat from a cooling chamber on its opposite side, which has been previously fired, aids in the combustion of the fired chamber. That is, outside air is drawn in through the cooling chamber, and being heated by the previously fired chamber and burned ware therein, it is conducted for a considerable period 20 through the perforated flues of said cooling chamber into the radiating flues of the chamber being fired and up over the fuel in the bags 6 of said chamber, thereby materially promoting the combustion, whether 25 the fuel be coal, oil or gas.

By the arrangement of alternating perforated and radiating flues in the floor of each chamber, and having the perforated flue of one chamber communicating directly 30 with the radiating flue of an adjoining chamber on one side only, the communication is direct between said coöperating flues of two adjoining chambers and circulation may be established successively throughout the entire 35 row or rows of kilns; and uniform burning of the ware is accomplished by reason of the evenly distributed circulation due to the alternating and staggered arrangement of the coöperating perforated 40 and radiating flues of the adjoining chambers.

A kiln arranged as shown in the drawing is especially adapted for the use of oil or producer gas as a fuel and it may also be used with coal as a fuel, but it is preferable 45 to provide furnaces having grates at the openings 8 at the opposite ends of the bags 6 and also in the furnaces 3. However, coal may be thrown onto the bottoms 50 of the bags 6 and the draft through the openings 8 will be sufficient to promote combustion, especially as the heated air from the adjoining cooling chamber may be conducted into the fired chamber through 55 the flues 10 and 12 and openings 13 above the body of fuel. So, too, the kiln chambers 60 may be fired from both ends and the ashes can be easily removed from the bags 6.

In some cases, the imperforate radiating

flues may communicate direct into the bottoms of the bags 6. In such cases the flues 12 and openings 13 in the division walls may be eliminated; and obviously, the kiln admits of considerable further modification without departing from my invention. 70 Therefore I do not wish to be limited to the specific construction and arrangement shown.

What I claim is:

1. A continuous kiln comprising a series 75 of adjoining burning chambers, each of said chambers being provided on opposite sides adjacent to the respective division walls with bags whose lower portions constitute a furnace, the floors of said chambers being provided with a multiplicity of longitudinal flues, the floors having a multiplicity of openings communicating with alternate flues, the open floor flues of the respective chambers being direct continuations of the 80 imperforate floor flues of the adjoining burning chambers, the division walls between said chambers having uptake flues therein communicating at their lower ends with the respective imperforate floor flues 85 and at their upper ends with the respective bags above the lower portions thereof.

2. A continuous kiln comprising a series 90 of adjoining burning chambers, each of said chambers being provided on opposite sides 95 adjacent to the respective division walls with bags whose lower portions constitute a furnace, the floors of said chambers being provided with a multiplicity of longitudinal flues, the floors having a multiplicity 100 of openings communicating with alternate flues, the open floor flues of the respective chambers being direct continuations of the imperforate floor flues of the adjoining burning chambers, the division walls 105 between said chambers having uptake flues therein communicating at their lower ends with the respective imperforate floor flues and at their upper ends with the respective bags above the lower portions thereof, the 110 side wall of the kiln being provided with openings communicating with the ends of said bags at the lower portion thereof.

3. A continuous kiln comprising a series 115 of adjoining burning chambers, each of said chambers being provided on opposite sides adjacent to the respective division walls with bags whose lower portions constitute a furnace, the floors of said chambers being provided with a multiplicity of longitudinal flues, the floors having a multiplicity of 120 openings communicating with alternate flues, the open floor flues of the respective chambers being direct continuations of the imperforate floor flues of the adjoining burning chambers, the division walls 125 between said chambers having uptake flues therein communicating at their lower ends

with the respective imperforate floor flues and at their upper ends with the respective bags above the lower portions thereof, draft creating means for the respective burning chambers connected with the open floor flues thereof, and means for controlling the draft of said chambers individually.

Signed at St. Louis, Missouri, this 7th day of February, 1911.

WALTER P. GRATH.
